UNITED STATES PATENT OFFICE.

JOSEPH ADKINS, OF HILLSBOROUGH, INDIANA, ASSIGNOR OF ONE-HALF TO
AUSTIN R. FRAZIER, OF SAME PLACE.

DESIGN FOR A NAIL-SET.

SPECIFICATION forming part of Design No. 33,792, dated December 25, 1900.

Application filed February 2, 1900. Serial No. 3,762. Term of patent 14 years.

To all whom it may concern:

Be it known that I, JOSEPH ADKINS, a citizen of the United States, residing at Hillsborough, in the county of Fountain and State of Indiana, ⁵ have invented and produced a new and original Design for a Nail-Set, of which the following is a specification.

This invention relates to a new and useful design for a nail-set; and the essential feature ¹⁰ resides in the design as illustrated in the accompanying drawings, wherein is shown a perspective view of the nail-set embodying the invention.

In the drawings, Figure 1 is a perspective ¹⁵ view of a nail-set embodying the present design. Fig. 2 is an end elevation thereof.

The elongated gradually and regularly tapered body 1 has a reduced extremity 2 and an opposite enlarged end 3, and adjacent the ²⁰ latter end the said body is intersected by a shorter regularly-tapered shank 4, which is in a plane at a right angle to the said body and has a greater portion extended from one

side of the latter than from the opposite side. Both the shank and the body are rounded in ²⁵ cross-section, and the shank has an enlarged end 5 close to the enlarged end 3 of the body, and both enlargements have flat outer terminals of circular form. The body and the shank also taper continuously from their enlarged ends to their reduced ends, and the enlarged end 5 of the shank is the sole projection from its side of the body 1 and sets in close to the latter, thereby producing an approximate L-shaped device. ³⁰

Having thus described the invention, what is claimed as new is—

The design for a nail-set, as herein shown and described.

In testimony that I claim the foregoing as ⁴⁰ my own I have hereto affixed my signature in the presence of two witnesses.

JOSEPH ADKINS.
